Ronald J. Waterbury, Birmingham, Mich., as-
signor to General Motors Corporation, Detroit,
Mich., a corporation of Delaware

Application February 14, 1940, Serial No. 90,248

Term of patent 7 years

To all whom it may concern:

Be it known that I, Ronald J. Waterbury, a citizen of the United States, and a resident of Birmingham, county of Oakland, and State of Michigan, have invented a new, original, and ornamental Design for an Automobile Front Fender, of which the following is a specification, reference being made to the accompanying drawing forming a part thereof.

Figure 1 is a plan view of an automobile front

fender for an automotive vehicle showing my new design.

Fig. 2 is a side elevational view of the fender.

Fig. 3 is a front elevational view of the fender

Fig. 4 is a section on the line 4—4 of Figure 3.

I claim:

The ornamental design for an automobile front fender, as shown.

RONALD J. WATERBURY.
